MACHINE FOR BREAKING IN SHOES

Samuel Segal, New York, N. Y., assignor of one-third to C. M. Palmer, New York, N. Y.

Application April 7, 1932, Serial No. 603,741

10 Claims. (Cl. 12—17)

The present invention relates to shoe shaping and forming, and particularly relates to apparatus and mechanisms which are adapted to break-in new shoes and conform shoes in general to the foot of the wearer.

In breaking in shoes it has been customary to utilize the wearer's foot as a breaking-in instrument with much resultant discomfort and distress to the person concerned. Many shoes require breaking-in over long periods of time and to complete the process it is necessary for the wearer to use them at as frequent intervals and for as extended periods as may be tolerated without acute distress, and often as a result of this breaking-in process permanent foot ailments or deformities arise.

Some attempt was made to hasten such breaking-in processes by placing the shoes on expanding heads or forms and/or by hammering the soles. Such expanding devices generally stretch the shoe in places, where no particular relief is needed and moreover frequently disfigure the shoe. As a result of such stretching devices, creases are often formed on the vamp which are extremely difficult to smooth out; the upper of the shoe is disfigured; and seams and stitches are strained so that the life period of the shoe is shortened and the appearance of the shoe is disadvantageously affected. These stretching devices usually have no substantial effect upon the sole itself, where a great deal or most of the difficulty arises. On the other hand hammering devices do not effect satisfactory reshaping or reforming of the shoe and both the life period and the appearance of the shoe are also disadvantageously affected.

An object of the present invention is to provide an inexpensive rugged and readily-operable apparatus for breaking-in shoes, and particularly for forming or shaping shoes to the feet of the wearer, which will not disadvantageously affect the shape of the shoe, which will not stretch the seams or break the stitches thereof, and which will not shorten the life period of the shoe, all without need of subjecting the upper of the shoe to stretching and without necessitating any substantial breaking-in process by the wearer or purchaser.

Another object is to provide a device for shaping and treating the inner faces of the forward part of soles of shoes to cause them to conform to the shape of the bottom of the foot of the wearer and to render a new shoe immediately comfortable for wear, which device is readily adapted to practically any size or shape of shoe either for men,

women or children, all without the need of complicated adjustments, readily becoming disorganized and necessitating the skillful attention of a trained worker and without the necessity of subjecting the inner faces of the soles to subsequent smoothing or secondary forming and/or shaping operations.

Another object is to provide a machine of the character described in which the shoe may be formed and shaped for an extended period of time without continued manipulation of the machine to prevent slippage, easing or displacement of the gripping faces, which machine may be readily set into forming or shaping position, locked into such position and subsequently released with a maximum of ease and convenience by relatively simple manually controlled actuating arrangements.

Another object is to provide a rugged machine of the character described which will stand up under considerable usage and rough handling, and which when disorganized or out of adjustment, may be readily repaired and readjusted by the removal and replacement of relatively few and inexpensive parts.

Other objects are in part obvious and in part pointed out hereinafter.

In one embodiment of the present invention, the mechanism or machine is provided with a stand or supporting frame having a swinging head which may be latched into position and a vertically adjustable anvil, which anvil and head member may be both conveniently located at about the proper height for the operator.

The anvil member is preferably constructed so that it may be readily replaced by other anvil members having clamping portions of different sizes and shapes to receive the front portions of a wide variety of shoes, and it also may be provided with ledges, grooves or lips upon its upper surface to receive and position a series of embossed shaping and forming pressure plates which are to be pressed against the inner sole.

Although the anvil or last member may be vertically adjusted by any suitable arrangement it is preferably manipulated by a hydraulic cylinder, desirably associated with a lever for manual operation. In the form shown the lever may be telescoped inside of the machine when not in use, it need only be withdrawn when the hydraulic device is to be actuated, the hydraulic device being actuated by a vertically swinging movement of the lever. In the preferred embodiment the hydraulic cylinder is enclosed and concealed within the support or stand structure.

When a hydraulic device is utilized to prevent the cushioning thereof, which will permit loosening of the shoe and slippage between the anvil and the swingable head of the machine, a locking means is provided, either automatically or manually actuated, to hold the anvil or last member firmly in position against the bottom of the head with the front portion of the shoe firmly gripped therebetween. In the form shown the anvil or last member is locked into clamping position by a screw device provided with a hand knob or wheel.

The elongated head of the machine is preferably hinged at one end to an upward extension of the stand so that it might be swung away to permit removal of the shoe and toward the anvil member after the next shoe to be shaped and formed has been placed upon the anvil. The head is provided with a substantial depending latch which cooperates with a corresponding projecting lip on the stand to hold the head firmly in position against the upward pressure of the anvil member.

The contacting surface of the head is preferably provided with a replaceable flat pressure plate, which will withstand considerable pressure, and which, when deformed, may be readily removed for repair and replacement purposes.

Each machine is preferably provided with a series of different shapes and sizes of anvil members for correspondingly different sizes and shapes of shoes, and also with a number of flat and embossed pressure plates which may be readily placed upon the top of the anvil member. These plates may be provided with suitable positioned and sized embossments, projections and elevations for shaping the shoe as may be desired, as for example to form depressions in the sole of the shoe for one or all of the toes, for boxing the shoes, for smoothing out the inner sole, for rendering the shoe easier to wear for a person having slight deformities, as for example callouses, bunions, and bunionettes particularly between the ball and the instep, and around the cuboid bone and for generally breaking-in new shoes and shaping or forming them to the wearers' feet.

In the drawings which illustrate one embodiment of the present invention,

Fig. 1 is a side elevation of the machine upon its stand;

Fig. 2 is a side sectional view upon the line 2—2 of Fig. 1; and

Figs. 3 and 4, Figs. 5 and 6, Figs. 7 and 8, Figs. 9 and 10 and Figs. 11 and 12 are respectively top and sectional views upon the lines 4—4, 6—6, 8—8, 10—10 and 12—12 of Figs. 3, 5, 7, 9 and 11, showing several modifications of the wide variety of the different sizes, shapes and forms of the complementary pressure plates, which may be removably positioned on top of the anvil member.

In Figs. 1 and 2 the stand 10 is provided with a base plate 11 and carries at its upper end a frame 12, which is provided with an enclosure or casing 13 receiving the hydraulic cylinder 14. The piston 15 of the hydraulic cylinder 14 is actuated by the handle 16 which is provided with an outer knurled gripping surface 17. The handle 16 slides in the block 18 and may be placed in withdrawn position as indicated by the dot and dash lines 19 when not being utilized, the pins 20 and 21 limiting the movement of said handle in said block 18.

Provision has been made for regulating the displacement of the anvil in a direction towards the head 42 on each effective stroke of the handle 17.

To this end the leverage of the handle may be regulated to impart the desired pressures in back of the piston 15. For this purpose the handle includes a plurality of spaced annular grooves 17' and these selectively cooperate with a shank 21' connected to and actuated by the manipulator wheel 18', the shank 21' being adjustably carried by block 18. It is therefore apparent that the leverage of the handle may be varied by arranging shank 21' in any one of its several annular 10 grooves.

The block 18 also receives the stud 22 which has a head 23 pivotally connected to the link 24 at its innermost end 25 and also pivotally connected to the piston 26 at 27. The piston 26 fits into the cylinder 28 by which a liquid, such as oil, may be forced into the hydraulic cylinder 14. The hydraulic cylinder 14 is provided with a release valve 29 which is actuated by the knob 30.

The upper portion of the frame 12 is provided with a cylindrical guide 31, which receives the depending shank or stud 32 depending from the last or anvil member 33 shaped complementally to a portion of a shoe. The lower end 34 of the stud 32 rests upon and contacts with the top of the piston 15 of the hydraulic cylinder 14.

The upper portion of the anvil member is shaped to the front portion of the shoe which is to be received or placed thereupon. The top of the anvil or last member 33 has a projecting ledge 35 or lip 35 which is shaped to receive the replaceable pressure plates 36, and the type more fully shown in Figs. 3 to 12. These plates are each correctly positioned upon the ledge 35 by the vertically depending lip 37 at their front ends and by the curved downturned portion 38 at their rear ends, curved portion 38 having a depending terminal fitting along the rear slightly inclined vertical end face of ledge 35 of the anvil and cooperating with the latter to prevent longitudinal 40 displacement of a respective pressure plate placed on the anvil.

The upper part of the structure 12 is provided with an upstanding extension 39, the upper portion of which receives the pivot rod or pin 40 forming a pivotal connection with the downturned end 41 of the elongated head member 42.

The other end of the head is similarly provided with a pin or rod 43 which pivotally or swingably connects the depending link or latch 44 with the head 42, the laterally extending handle 45 carried by the latch serving to enable manipulation of said latch 44. The structure or frame 12 is provided with the outward extension or lip 46 overhanging a side thereof, which lip cooperates and interlocks with the concavity 47 in the latch 44 to hold the same firmly in position. For purposes of specification, latch 44 may be considered as a socket or housing for removably enclosing overhanging lip 46. The contacting face of the head 48 is provided with the replaceable pressure resisting plate 49, which may be readily removed and replaced by loosening the screws 50.

To lock the anvil member in clamped position, the depending shank 32 of the anvil member 33 is provided with a tapered slot 51 which cooperates with the end of the threaded shank 52 having the adjusting wheel or knob 53. The end 54 of the shank 52 may be firmly clamped against the vertically inclined face of the tapered slot 51 by 70 turning of the knob 53 to prevent movement of the anvil member when it has gripped the sole of the shoe against the complementary clamping plate 49 contacting head 42.

In Figs. 3 to 12 are shown various shapes and 75

forms of pressure plates which may be positioned on top of the anvil or last member 33. These pressure plate members are all provided with the vertically depending inturned peripheral relatively thin lips or flanges 37, which fit along the sides and front of the ledge 35 of the last or anvil 33 and while the terminal of the downwardly curved portion fits along the rear end of the ledge 35 of the anvil as in the case of the pressure plate 36 shown in Fig. 2 and in the latter as is well understood, plate 36 may be provided with an integral enlargement or boss of the types illustrated in Figs. 3-10 inclusive.

Figs. 3 and 4 show an elevation or projection 55, integral with the base or body 56, which is particularly adapted to fit or form shoes for persons afflicted with callouses and bunions or small bunions around the cuboid bone or at the metatarsal region.

20 In Figs. 5 and 6 the boss 57 is particularly adapted to form an indentation or depression for the large toe in the inner face of the sole of the shoe.

The elevation 58 of Figs. 7 and 8 is particularly adapted to form a depression for all of the toes and/or for boxing the shoes.

25 The elevation 59 of Figs. 9 and 10 is particularly adapted for molding the sides of the shoe and smoothing out the inner sole along the side edges of the shoe.

30 Figs. 11 and 12 show a modified pressure plate structure in which the pressure plate is made in two parts. A flat member 60 has downturned lips 61, which lips function the same as the previously described lips 37, to hold the pressure plate 60 upon the ledge 35. The plate of Figs. 35 11 and 12 is provided with a removable boss member 62 which has an inturned lip 63 for holding it in position upon the side of the pressure plate 60. The particular boss or elevation shown is for shaping the side of the shoe and also for condensing or depressing the inner sole at that point.

40 It will be noted that the pressure plate removably mounted on the anvil of the types illustrated in Figs. 1 to 10 inclusive, each comprise a body having a width and length substantially co-extensive with the width and length of the anvil, the body having a forward relatively flat portion from which integrally projects an enlargement having an external relatively smooth surface extending above the upper surface of the flat portion. The body also includes a rearwardly disposed downwardly curved portion integrally connected with the flat front portion, the curved and flat portions having lower merging surfaces complementary to the upper surface of the anvil and the body comprises the peripheral flange having depending portions extending downwardly, transversely and longitudinally relative to the anvil and adapted to fit over and engage the latter, that is, the body embodies peripherally disposed depending means to permit locating thereof on the anvil.

45 In operation assuming that the piston 15 and the anvil member 33 to be in their lowest positions after operation of the release valve 29, the desired pressure plate is positioned on top of the ledge 35 of said anvil member and the shoe is placed in position. The head 42 is then lowered and the latch 44 permitted to fall in position below the lip 46. Then the handle 20 is withdrawn and by a series of rapid reciprocating movements, the piston 26 is actuated to force

5 liquid into the hydraulic cylinder 14 and elevate the piston 15 and the anvil member 33.

When the shoe is firmly gripped in position under the satisfactory amount of pressure, the locking device 53 may then be screwed into position to prevent any release or downward movement of the anvil member 33. It will be noted that upward movement is permitted and additional pressure may be placed upon the shoe by continued manipulation of the handle 17.

10 The plate 49 being flat will prevent any scarring or marking of outside of the sole of the shoe and will assist the embossings or projections upon the pressure plates of the type shown in Figs. 3-12 inclusive in suitably forming the inside of the sole of the shoe.

When the operation has been completed the locking member 53 is unscrewed, and the valve 29 is turned to permit descent of the anvil, whereupon the latch 44 may be removed and the head 20 member 42 may be swung away permitting removal of the shoe.

25 If any mistake has been made, the inside of the shoe may be readily smoothed by utilizing a flat pressure plate, such as the plate 60 of Figs. 11 and 12 without the boss 62 (see, for example, Fig. 2).

The flat plate 49 of the head 42 is subjected to considerable pressure and stress and may be bent after a period of usage. If it is so bent it 30 may be readily removed by loosening the screws 50 and a new plate may be put into position.

35 The shoe forming and shaping apparatus or device of the present invention is particularly advantageous inasmuch as pressure is applied 35 against the inside of the sole of the shoe which is to be shaped or formed, and inasmuch as such pressure may be continued or intensified for a continued period depending upon the length of 40 time necessary to do a satisfactory job.

40 It is not necessary to use any adjustable or replaceable elements, which require the utilization of holes or grooves upon the face of the last or pressure plate, and which would tend to mar the inside of the shoe and form a large 45 number of unnecessary and undesirable projections therewithin. Moreover, the shoe may be readily adjusted upon the last or anvil member and may be slid into its proper position without danger of causing a disarrangement or maladjustment of the shaping projections, inasmuch as such shaping or forming embossings are integral with the forming plate, or are attached thereto as in Figs. 11 and 12, will be permanently held in position and will not tend to slip 50 or become displaced.

45 The device is also particularly desirable in utilizing a flat plate, instead of a curved or other uneven surface on the contacting face of the head, with the result that even though substantial pressures are applied to the bottom of the 60 sole of the shoe it will not be marred or defaced.

55 As many changes could be made in the above construction, and many apparently widely different embodiments of this invention could be 65 devised without departing from the scope thereof, it is intended that all matter contained in the above description or shown in the accompanying drawings shall be interpreted as illustrative and not in a limiting sense.

60 Having thus described my invention what I claim as new and desire to secure by Letters Patent is:

65 1. In a machine for breaking in shoes, the combination of, a supporting frame, a head 75

- member having a clamping element, an anvil member slidable relative to said frame, means to adjust one of said members in respect to the other, pressure means to be removably positioned on said anvil member and adapted to support the object to be processed interposed between said pressure means and the clamping element of said head member, said adjusting means including a hydraulic arrangement, and means to lock said anvil member in clamping position, said pressure means being substantially co-extensive with the width and length of said anvil member and having integrally depending portions removably cooperating with said anvil member to prevent longitudinal and transverse displacement of said pressure means relative to said anvil member.
2. In a machine for breaking in shoes, the combination of, a supporting frame, a head member having a clamping element, an anvil member slidable relative to said frame, means to adjust one of said members in respect to the other, pressure means to be removably positioned on said anvil member and adapted to support the object to be processed interposed between said pressure means and the clamping element of said head member, said supporting frame including a vertical guide and said anvil member having a depending projection to removably fit into said guide, and means to lock said depending projection to prevent downward displacement of the latter, said pressure means being substantially coextensive with the width and length of said anvil member and having a lower surface substantially complementary to the upper surface of said anvil member and including an arcuately shaped enlargement integral with the body of said pressure means, said pressure means having longitudinally extending integrally connected flanges depending from the sides thereof and cooperating with the sides of said anvil member to prevent transverse displacement of said pressure means relative to said anvil member.
3. In a machine for breaking in shoes, the combination of, a supporting frame, a head member having a clamping element, an anvil member slidable relative to said frame, means to adjust one of said members in respect to the other, pressure means to be removably positioned on said anvil member and adapted to support the object to be processed interposed between said pressure means and the clamping element of said head member, said supporting frame including a vertical guide and said anvil member having a depending projection to slidably and removably fit into said guide, and said guide being provided with a threaded stud and said projection being provided with a tapered slot of increasing depth downwardly, said stud and said slot cooperating to lock said anvil member against downward movement.
4. An apparatus for breaking in shoes, and for shaping and forming them, comprising in combination, a support, a vertically adjustable anvil member with a form shaped to receive a shoe and with a cylindrical depending shank, a guide on said support to receive said shank, manually controlled means below said guide to elevate or lower the lower end of said shank, a pressure plate with an integral elevation on the upper face thereof and with a depending lip around the periphery thereof to fit over said anvil member, and an overhanging upper pressure head pivotally connected to said support.
5. As a new article of manufacture, a one piece pressure plate shaped to contact the inside surface of the forepart of a shoe and adapted to be supported on a complementally shaped anvil; comprising an elongated body having a forwardly disposed relatively flat portion and an integrally connected rearwardly disposed downwardly curved portion, said portions having lower surfaces complementary to the upper surface of said anvil, said flat portion having an externally curved enlargement integral with said body and extending above the upper surface of said flat portion, said body having a width slightly greater than the width of said anvil and having longitudinally extending depending means adapted to removably engage the sides of said anvil to prevent transverse displacement of said plate.
6. As a new article of manufacture, a one piece elongated pressure plate comprising a body having an upper surface to support the inner sole portion of the forward part of a shoe, and having a lower surface complementary to the upper surface of an anvil, shaped complementally to the forward part of said shoe; said body comprising a forwardly disposed relatively flat portion and an integrally connected rearwardly disposed downwardly curved portion; said flat portion having a relatively smooth externally curved enlargement integrally connected with said body and extending above the upper surface of said flat portion; said body having a width and length substantially co-extensive with the width and length respectively of said anvil and having longitudinally extending relatively thin depending flanges adapted to straddle and removably engage the sides of said anvil.
7. As a new article of manufacture, a one piece pressure plate; comprising an elongated body having an upper surface to support the inner sole portion of the forward part of a shoe and a lower surface complementary to an upper surface of an anvil shaped substantially complementary to the forward part of said shoe, said body comprising a forwardly disposed relatively flat portion and an integrally connected downwardly curved portion, said flat portion having a relatively smooth externally curved enlargement integral with said body and having an upper surface extending above the upper surface of said flat portion, said body having a width and length substantially coextensive with the width and length respectively of said anvil and having longitudinally extending flanges integrally depending from the sides of said body and adapted to removably engage the sides of said anvil.
8. In a machine for breaking in shoes, the combination of, a frame having a pivoted head, a depending latch swingably connected to said head, a laterally extending lip integral with said frame and overhanging a side wall thereof, an anvil having a depending shank slidably guided by said frame, a relatively flat pressure resisting plate contacting a lower horizontal face of said head and secured thereto, a pressure plate removably mounted on said anvil comprising a body having a width and length substantially coextensive with the width and length of said anvil and including a raised externally curved enlargement integral with said body and extending above a relatively flat upper surface of

- the latter, said body having spaced longitudinally extending relatively thin integrally depending flanges adapted to engage the sides of said anvil to prevent transverse displacement of said body 5 relative to said anvil, said body and anvil having means to prevent longitudinal displacement of said body relative to said anvil, said latch comprising a housing for removably receiving and interlocking with said lip in the closed position 10 of said head, pressure producing means for moving said anvil towards said head for changing the shape of a sole of a shoe interposed between said enlargement and said flat pressure plate secured to said head, and a laterally extending handle carried by said latch. 15
9. In a machine for breaking in shoes, the combination of, a frame having a pivoted head, a depending latch swingably connected to said head, a laterally extending lip integral with said frame and overhanging a side wall thereof; an anvil formed complementary to a part of a shoe, having a depending shank slidably guided by said frame, a relatively flat pressure resisting plate contacting a lower horizontal face of said head and secured thereto, a pressure plate removably mounted on said anvil comprising a body having a length substantially coextensive with the length of said anvil and a width substantially coextensive with the width of said anvil, said body comprising a relatively flat front portion and an integrally connected downwardly curved rear portion, said portions having merging lower surfaces complementary to the upper surface of said anvil, said flat portion having an integral externally curved relatively smooth enlargement having an upper surface extending above the upper surface of said flat portion, said body having spaced longitudinally disposed relatively thin flanges integrally depending from the sides of said body 25 and adapted to straddle and removably engage
- the sides of the anvil, said latch comprising a housing for removably receiving and interlocking with said lip in the closed position of said head, manually controlled pressure producing means cooperating with said shank for bodily moving said plate removably mounted on said anvil and said anvil towards said head for changing the shape of a sole of a shoe interposed between said enlargement and said pressure plate secured to said head, and a laterally extending handle carried by said latch. 30
10. In a machine for breaking in shoes, the combination of, a frame having a pivoted head, a depending latch swingably connected to said head, a laterally extending lip integral with said frame and overhanging a side wall thereof, an anvil having a depending shank slidably guided by said frame, a relatively flat pressure resisting plate contacting a lower horizontal face of said head and secured thereto, a pressure plate removably mounted on said anvil comprising a body having a length substantially coextensive with the length of said anvil and a width substantially coextensive with the width of said anvil and including a raised externally curved enlargement 35 integral with said body and extending above a relatively flat upper surface of the latter, said body having spaced longitudinally extending relatively thin integral depending flanges adapted to engage the sides of said anvil, said latch comprising a housing for removably receiving and interlocking with said lip in the closed position of said head, pressure producing means for moving said anvil towards said head for changing the shape of a sole of a shoe interposed between said enlargement and said flat pressure plate secured to said head, and a laterally extending handle carried by said latch. 40

SAMUEL SEGAL.

40
